UNITED STATES PATENT OFFICE.

GEORGE H. PERRYMAN, OF NEW YORK, N. Y., ASSIGNOR TO PERRYMAN ELECTRIC COMPANY, INC., OF NEW YORK, N. Y., A CORPORATION OF NEW YORK.

VACUUM TUBE.

Application filed November 3, 1925. Serial No. 66,553.

This invention relates to an improvement in a vacuum tube intended particularly for radio purposes and has for its object to provide a tube of this character in which the various internal elements or parts will be strongly reinforced and held together so that the electrical characteristics of the tube will not be changed by the shifting of the parts relative to one another by reason of rough handling or use.

A further object of this invention is to provide a reinforcing or bracing means for the parts of a vacuum tube so that said parts cannot readily shift or change their positions relative to one another, thus providing an extremely strong and substantial tube capable of withstanding rough handling or abuse.

With these objects and such other objects as may hereinafter appear, in view, I have devised the particular arrangement of parts hereinafter set forth and more particularly pointed out in the claims appended hereto.

Reference is to be had to the accompanying drawings, forming a part hereof in which—

Figure 1 is a front elevation of the interior parts of the tube, certain parts being shown in section to disclose construction;

Figure 2 is a plan view of the same;

Figure 3 is a perspective view of the upper bracing strip; and

Figure 4 is an end view of parts of the tube.

Throughout the various views of the drawings, similar reference characters designate similar parts.

In the preferred embodiment of my invention, 1 indicates the tube base or stem which is preferably of glass and which, in the usual construction of tubes extends downward and unites with the usual glass enclosure shell which has been omitted from the drawing. The stem or base 1 is moulded about and holds upwardly extending wires or rods 2 which carry the usual enclosing plate member 3.

At 4 are shown a pair of wires which project upward out of the base 1, and these wires 4 are splayed outwardly and are fused to upwardly projecting rods or wires 8 around which the grid 5 is wound, said grid being located within the plate 3 as is customary in vacuum tube construction.

At 9 is shown a bracing member which

may be made of mica or any other desired insulating material and this strip acts as a supporting and bracing member for the various tube elements. Said strip 9 is provided with perforations 16 through which the plate-supporting wires 2 extend upwardly and it is also provided with a pair of perforations 15 through which the grid supports 8 extend. Said strip 9 is also provided with a pair of perforations 17 through which wires 6 extend, said wires 6 projecting upward and out of the base 1 in which they are anchored.

It will be seen that the brace member 9 rests upon the outwardly splayed ends of the wires 4 and it is held thereon by the plate 3 whose lower edge rests upon the upper face of the strip 9.

At 10 is shown a similar bracing strip which is located at the upper ends of the various wires and said strip is provided with the various perforations 15 and 16 to receive the upper ends of the wires 8 and 2.

It is noted that the wires 2 are projected slightly beyond the upper face of the strip 10 so that said projecting ends may be bent over to hold the strip 10 down upon the upper end of the plate 3 and prevent the strip 10 from being detached.

In the strip 10 is located a central perforation through which a wire formed on the end of the coil spring 11 projects. Said wire terminates in a hook 12 which acts to engage and resiliently support the upper end of the filament 7.

It will be noted that the spring 11, which is an inverse coil spring, rests upon the upper face of the bracing strip 10.

It will be apparent from the foregoing that through the use of the bracing strips 9 and 10, an extremely secure and rigid construction is afforded. The plate 3 is securely held between the strips 9 and 10 and has its opposite ends abutting against said strips and holds them apart. The various wires which support the grid, the plate and the filament pass through suitable perforations in the strips 9 and 10 with the result that said wires are always held accurately spaced from one another and cannot shift or change their relative positions by rough handling or abuse of the tube.

Having described one embodiment of my invention, it is obvious that the same is not to be restricted thereto, but is broad enough

to cover all structures coming within the scope of the annexed claims.

Having described my invention, what I claim is:

- 6 1. In an article of the class described, a base, a pair of plate supporting wires extending therefrom, grid supporting wires extending therefrom and filament supporting wires extending therefrom, a strip of 10 insulating material located adjacent said base, said strip having a plurality of perforations through which the various wires project, said strip resting upon and supported by parts of the grid-supporting wires, 15 an upper strip of insulating material at the ends of the various wires, the ends of some of said wires being bent over on the upper face of said strip so that said upper strip rests upon the upper end of the plate, and 20 means held upon said upper strip for engaging and resiliently supporting the upper end of the filament.
2. In an article of the class described, a base, plate supporting wires extending upwardly therefrom, a plate carried on said wires, grid-supporting wires extending from said base, said grid-supporting wires having outwardly splayed portions on which a strip of insulating material rests, and an upper

strip of insulating material through which 30 the plate-supporting wires and grid-supporting wires extend, said upper strip resting on top of the upper edge of the plate and held thereon.

3. In a vacuum tube, the combination 35 with a base, plate-supporting wires extending therefrom, grid-supporting wires extending therefrom, a grid held on said grid-supporting wires, a filament, relatively narrow spaced insulating strips carried upon the 40 plate-supporting wires and on the grid-supporting wires, said strips each having a pair of openings through which the grid-supporting wires extend and also having another pair of openings through which the plate-supporting wires extend, a plate carried upon the plate-supporting wires and enclosing the grid and filament, said plate having its lower end resting upon the upper face of one of the insulating strips and having its 45 upper end bearing against the lower face of the other insulating strip whereby said insulating strips are maintained in spaced-apart relationship.

Signed at New York city, in the county 50 of New York, and State of New York.

GEORGE H. PERRYMAN.
